UNITED STATES PATENT OFFICE.

LLEWELLYN E. JONES, OF SYRACUSE, NEW YORK.

HAME.

SPECIFICATION forming part of Letters Patent No. 242,653, dated June 7, 1881.

Application filed May 11, 1881. (No model.)

To all whom it may concern:

Be it known that I, LLEWELLYN E. JONES, a citizen of the United States, residing at Syracuse, in the county of Onondaga and State of New York, have invented a certain new and useful Improvement in Hames, of which the following, taken in connection with the accompanying drawings, is a full, clear, and concise description of the invention, so that any person familiar with the art may make and use the same.

My improvement relates to what are known as "ball" or "bell-top" hames; and it consists in the peculiar construction of the clip for the top of the hame, which carries a ball, or a suitable frame for a bell, as will be hereinafter described.

Referring to the drawings, Figure 1 is a side elevation of the top of the hame with my improved ball-clip, and showing its relation with the back iron. Fig. 2 is a detached view of the ball-clip.

A represents the wooden hame. B is the clip, and C is the customary wrought back iron. The ball top or clip is formed of a single piece of metal and provided with two prongs or legs, *a a'*. One of the legs of the clip is recessed its entire length, as shown at *b*, leaving a shoulder, *c*, at the neck or shank, above which is formed a ball, a frame for a bell, or other suitable ornament. The leg or prong *a* is let into the wood of the hame at the top, and the wrought back iron, C, is extended to the shoulder *c* on the clip, covering the entire prong, thus making a double thickness of iron at the back of the hame at its top portion. The other prong, *a'*, is fitted to the wood on the inside of the hame, and the clip and back

iron are secured by rivets, which are passed through both legs of the clip, the wood comprising the hame, and the back iron.

In the ordinary construction the clip is formed with the two prongs or legs substantially alike, instead of having one of them recessed, and is secured to the wood by tenoning or chucking, and the back iron either only extends to the end of the clip or is attached to it. By this mode of securing the clip the hame is so weakened at the top that it is frequently broken off—a difficulty that is wholly obviated by my improvement, as my back iron runs clear to the top of the hame, making two thicknesses of metal at that point, and I am thus enabled to produce a hame the wood of which is not weakened, and the top of which, therefore, is not liable to be broken off.

By the use of my improved clip I construct a strong, cheap, and durable ball-top hame which entirely overcomes the objection hitherto made to hames of this character.

Having thus fully described my invention, what I claim is—

1. A hame provided with a ball top or clip, the back prong or leg of which is recessed, as described, in combination with the back iron, which is fitted into said recess, and the parts secured together by fastenings passed through all of them, as set forth.

2. A ball top or clip for hames provided with two prongs or legs, one of which is recessed and adapted to receive the customary back iron or facing, substantially as described.

LLEWELLYN E. JONES.
